Primary Examiner — Rosemary K Tarcza*Assistant Examiner* — Christy Nemeth*(74) Attorney, Agent, or Firm* — Mark V. Loen(57) **CLAIM**

The ornamental design for an extension cord connector lock, as shown and described.

DESCRIPTION

FIG. 1 is a front view of an extension cord connector lock of my new design;

FIG. 2 is a left side view thereof, the right side view being a mirror image;

FIG. 3 is a rear view thereof;

FIG. 4 is a top view thereof;

FIG. 5 is a bottom view thereof;

FIG. 6 is a bottom, right side isometric view thereof;

FIG. 7 is a second bottom, right side isometric view thereof, shown with the extension cord connector lock in a state of use; and,

FIG. 8 is a third bottom, right side isometric view thereof, shown with the extension cord connector lock in an open position.

The broken lines shown in FIG. 7 are for the purpose of illustrating environmental subject matter that forms no part of the claimed design.

1 Claim, 5 Drawing Sheets(56)
